CLAIM

The ornamental design for an ornamental pillow, as shown and described.

DESCRIPTION

FIG. 1 is a first perspective view of my ornamental pillow; FIG. 2 is a top plan view thereof;

FIG. 3 is a side view of my ornamental pillow taken between the top plan and bottom plan views; the side view being a mirror image of other side views taken between the top plan and bottom plan views;

FIG. 4 is a bottom plan view thereof;

FIG. 5 is a second perspective view of my ornamental pillow; and,

FIG. 6 is a cross-section view of my ornamental pillow taken along line 6—6 of FIG. 3.
